(57) **CLAIM**

The ornamental design for an apparatus for storing earphones, as shown.

DESCRIPTION

FIG. 1 is a top perspective view of the apparatus for storing earphones showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a side elevation view thereof;

FIG. 7 is an opposite side elevation view thereof; and,

FIG. 8 is a perspective view, shown in use.

Any broken-line illustration in the drawing disclosure is not a part of the design sought to be patented. Similarly, lines indicating shading are included for illustrative purposes to better perceive the three-dimensional structure of the claimed design but are not otherwise meant to be limiting in any manner.
